[57] CLAIM

The ornamental design for a diamond gauge set, as shown and described.

DESCRIPTION

FIG. 1 is a top and left front perspective view of a diamond gauge set showing my new design;

FIG. 2 is a rear elevational view thereof;

FIG. 3 is a top plan view thereof;

FIG. 4 is a left side elevational view thereof, the right side being substantially a mirror image thereto;

FIG. 5 is a front elevational view thereof.

FIG. 1.

FIG. 2.

FIG. 3.

FIG. 5.

FIG. 4.
